UNITED STATES PATENT OFFICE

121,464

DESIGN FOR A WINDOW GUARD

Margaret L. Anderson, Springfield, Ill.

Application November 10, 1939, Serial No. 88,202

Term of patent 7 years

To all whom it may concern:

Be it known that I, Margaret L. Anderson, a citizen of the United States and a resident of the city of Springfield, county of Sangamon and State of Illinois, have invented a new, original, and ornamental Design for a Window Guard, of which the following is the specification and reference being had to the accompanying drawing, forming a part thereof.

Fig. 1 is a perspective of a window guard showing my new design.

Fig. 2 is a front elevational view; and
Fig. 3 is an end view thereof.

I claim:

The ornamental design for a window guard, as shown.

MARGARET L. ANDERSON.
